INTENSITY CONTROL

Application filed August 6, 1927, Serial No. 211,084, and in Germany August 9, 1926.

Intensity variations or fluctuations due to atmospheric conditions are rather common in wireless telegraphy. While such fluctuations in reading telegraphy signals and in 5 telephony and also in high-speed reception with recorder devices still allow of comparatively good working conditions, especially when the text is sent twice, the phenomena in question known as fading are extremely disturbing in picture telegraphy and 10 apparently unavoidable even by repetitions of the message or text.

The present invention discloses ways and means whereby the influences of such fluctuations upon the quality of the pictures can be eliminated or at least greatly diminished. Fundamentally speaking, the invention consists in that in a system for transmitting and receiving pictures by radio, or 15 even land line, the receiver or the picture reproducing apparatus is given a changing 20 sensitiveness, the latter being adjusted in accordance with the prevailing intensity or volume of reception. Hence, if reception 25 is strong, the sensitivity must be made small, while the sensitivity must be great whenever the incoming signals are weak. This can be accomplished, for example, by providing a receiver arrangement with an integrating 30 grating action during a period which is long compared with the radio frequency period or picture-element period (fractions of a second), for example, a simple rectifier with collecting condenser produces a direct current 35 whose strength varies in conformity with the volume of reception, said direct current altering, for instance, in the shape of a grid potential, the sensitiveness of the picture reproducing apparatus in the desired manner. Since the fading or intensity fluctuations are generally of a period amounting 40 to several seconds, such an integrating device of low inertia is capable of compensating a large part of the intensity fluctuations.

Instead of deriving the regulating current in an integrating manner from part of the picture, the following method could also be used:

50 The picture is provided marginally with

a distinct or separate strip of medium blackness, consisting, for instance, of a shading as illustrated by portion S of the accompanying drawing. If, then, Z is the direction of the lines in the transmission of 55 the picture, for each line, during a certain fraction of the time, the mean transmission intensity which is produced by shading S will be present. More particularly speaking, the said strip S may be used for the purpose of adjusting the sensitiveness of the apparatus for the next line in the desired manner.

By the accompanying drawings we have shown by Fig. 1 one form which our invention may assume, and by Fig. 2 a modified form of the invention illustrating a different volume control system. It is to be understood, however, that such forms as are illustrated are purely by way of example, and we believe ourselves to be limited only in so far as is necessary from the scope of the invention as claimed.

In the embodiment shown by Fig. 1 of the drawings, signals from a transmitting station of somewhat similar characteristics to that of the receiver illustrated are received upon an antenna N and carried to a receiver and amplifying device, generally designated A. The output energy of the receiver and amplifier A is carried to a light source M where varying current strengths are adapted to produce light of varying intensity proportional to the incoming signal energy, and the produced light may be directed through lenses or any other preferred means to influence a light sensitive strip B on a receiving drum B'. The receiving drum B' is mounted upon a shaft C and is turned in any preferred manner by a motor or other means of known arrangement (not shown). The movement of the light source M is likewise accomplished by means of the same motor that rotates the drum B', and through a gear mechanism the motor is adapted to move the light source M back and forth upon a guide strip D at a speed which will be in synchronism with that of a similar light pick-up mechanism at the transmitting station. As the light source M moves back and 100

forth upon the guide strip D, upon reaching the end of each stroke means is preferably provided for advancing the drum B' a small fraction of an inch for recording the next 5 band of the picture on the light sensitive strip B. In the preferred embodiment of our invention the light sensitive strip B is provided at one edge (or even at both edges) with an area or strip of darkened 10 or shaded material S of which the intensity with which the light from source M for a given light intensity at the transmitter should shine through has been determined, since, at the transmitter a shaded strip or 15 area of like intensity to influence a light sensitive means controlling the transmitted energy is provided.

At the same time that the light source M has been moved so that it is above the darkened strip S of the light sensitive film B, a like movement has occurred at the transmitter, and as above stated the intensity of the light from M which should pass through the strip S to influence the photo cell P is 20 known provided there is no loss in received energy due to atmospherics, static, fading and other external influences such as might affect the incoming signal received upon the antenna N with the result that sufficient intensity of light from source M to produce the predetermined amount of illumination upon the photo cell P is unobtainable and means must be supplied to increase the sensitivity of the system to produce a finished 25 picture of even light distribution. Therefore, a standard of light intensity M' which is the same as that which is passed through a like strip S at the transmitter to influence the photo cell of the transmitter has been 30 provided, and each time that the light source M is advanced to reach the portion designated E of the guide strip D, a switch J is closed. The closing of switch J lights the source M' by means of a battery L'. The 35 switch J includes a conducting strip E which has been made a portion of the guide strip D and a conducting strip made a part of the portion M including the light source. The circuit for the light source M is closed 40 through parts E, K and the bottom contact of the switch J.

Light shining from the light source M' is carried through a screen S' of the same darkness as the screened or shaded portion 45 S which has been made a part of the light sensitive film B. The light from M' by means of lenses or other instrumentalities is directed to a photo cell P' and by which means a current is caused to flow owing to 50 the fact that the light changes the resistance properties of the photo cell. The currents flowing through photo cell P' are directed to an amplifier A' where amplification takes 55 place. Likewise the currents flow from the 60 photo cell P due to the influence of the light

from source M when the same has been moved across guide strip D to such a position that its light is directed upon the shaded portion S of the light sensitive film or strip B are directed to the amplifier A'' where 70 they are amplified. One terminal of each amplifier is preferably connected together and a connection between this common point and a magnetically controlled rheostat F provided with actuating coils H and H' at 75 the common point on said coils is made.

The other terminals of the amplifiers A' and A'' are connected to the free end of coils H' and H respectively. It is thus seen that if the current strength from each amplifier is the same, the currents flowing from the windings H and H' will be of equal 80 intensity and there will be no movement of the armature G of the magnetically controlled rheostat. However, if the current strength produced by the incoming signal energy to light the source M produces less intensity upon the photo cell P than the source M' produces upon the photo cell P, it is readily seen that the armature G will be 85 drawn toward the winding H'.

Associated with the receiver and amplifier A is a circuit in which the grid bias may be controlled automatically by means of the above named instrumentalities for variation 90 in light intensity of M over that of M', which variations may be produced by the commonly known characteristics of fading or other known effects. For any such variation, the sensitivity of the amplifying system A must be increased and, therefore, upon fading conditions taking place, the armature G will be drawn toward the winding H' in such a fashion as to decrease the amount 95 of resistance F in the grid bias control circuit which comprises the resistance F (forming a part of the magnetically controlled rheostat), the battery L and the grid circuits of certain tubes in the amplifier system A. Since the external influences of fading, static and all other disturbances 100 commonly known as strays, "X's", etc. do not usually occur with greater rapidity than the time required for source M to traverse the recording strip B, it is sufficient, in order 105 to obtain a finished picture of uniform intensity, to regulate the sensitivity of the receiving system at each stroke of the light source M across the film B. However, it is also within the scope of this invention to 110 control the sensitivity of the system by means of the shaded area S on each edge of the recording strip B, and such a form of invention will be substantial duplication of the elements herein set forth for a single 115 shaded area on one edge of the recording strip.

This system might also be controlled then by an operator to adjust the sensitiveness of the system in accordance with the current 120

flowing through the shaded portion S of the picture strip. This arrangement offers the merit that the regulating actions are more frequent so that compensation is affected 5 more rapidly than the one before described. To be sure, special change-over means are required in order that during the time S only the sensitiveness is regulated, whereas during the rest of the time the picture is 10 transmitted.

By Fig. 2, a modified form of arrangement is shown. This arrangement is substantially like the arrangement shown by Fig. 1 in that, signals are received upon the 15 antenna N and passed through the receiver and amplifier A where they are used to control intensity of a light source M for the purpose of producing a record upon a record strip B carried by the drum B'. In 20 parallel relation to the output terminals a, a of the receiver and amplifier A or, as shown by Fig. 2, in parallel to the input terminals e, e of the receiver and amplifier A, a separate rectifying and amplifying system 25 g is inductively coupled. This rectifying and amplifying system preferably consists in the usual type of the three electrode type vacuum tube for the purpose of producing an amplified and rectified current.

30 The radio frequency components remaining in the rectified current output of g is passed through a capacity element k and the direct current will flow through the inductance element d. The value of the direct current flowing is dependent upon the mean amplitude of the current derived from the signals impressed across the terminals e. The current flowing through the inductance d may be arranged to regulate, in any manner desired, by controlling the position of 35 a magnetizable core m, the value of a resistance r associated with the receiver and amplifier A so as to control the grid bias on the amplifier A and thus provide an arrangement 40 wherein the intensity of the received signal may regulate the sensitiveness of the picture reproducing apparatus in the desired manner. The arrangement shown by Fig. 2 forms an integrating device of low inertia 45 which is capable of compensating for a large 50 part of the intensity fluctuations.

Having thus described our invention, what we claim is:

1. The method of eliminating intensity 55 variations in radio picture transmission and reception which comprises providing an area of shade upon at least one edge of the picture and controlling the sensitiveness of a reproducing apparatus by the intensity of 60 reception on said area of shade at each line of the picture.

2. In an apparatus for eliminating intensity fluctuations in radio picture transmission and reception, means for receiving and 65 visibly recording messages, and light sensi-

tive means for automatically controlling the sensitivity of the receiving means in proportion to the mean intensity of signal reception at any given time period.

3. An apparatus for eliminating intensity 70 fluctuations in radio picture transmission and reception, comprising, means for receiving signals, means for recording messages in accordance with said received signals, means for automatically controlling the sensitivity of said picture receiving apparatus in proportion to the mean intensity of signal reception at any given instant, said means including a light sensitive means for controlling the grid bias on said receiving 75 apparatus.

4. An apparatus for eliminating intensity fluctuations in radio transmission and reception systems, comprising, light responsive means for automatically determining the 80 mean intensity of reception at predetermined time intervals, and means for controlling the sensitiveness of the receiving system in proportion to the deviations in the mean intensity at said predetermined time intervals from a predetermined normal intensity 85 of reception.

5. A system for receiving facsimile, including, means for producing light intensities of a value governed in accordance with 90 the intensity of reception at any given instant, means for periodically comparing the said light intensity produced with a constant predetermined normal light intensity value, and means controlled by variations in said 100 first named light intensity produced from said predetermined normal value of light intensity for controlling the sensitiveness of the said receiving system.

6. An apparatus for eliminating intensity 105 fluctuations in radio transmission and reception systems comprising, a light controlled means for determining the intensity of reception at predetermined time intervals, means for comparing the intensity of reception at said chosen time intervals with a normal standard of reception, and means for controlling the sensitiveness of the receiving system in proportion to the variations in 110 the mean intensity of reception from said predetermined normal standard value.

7. A system for receiving facsimile including, means for receiving signals and producing therefrom light intensities of a 115 value governed in accordance with the intensity of reception of any given instant, means for periodically comparing the said light intensity produced with a predetermined normal constant light intensity value, and means controlled by variations in said 120 first named light intensity produced from said normal value for applying a controlling bias to said receiving means for governing the sensitiveness of the said receiving system.

8. The method of eliminating intensity fluctuations in radio picture transmission and reception systems, which comprises, providing an area of shade upon at least one edge 5 of the picture, directing a light beam governed in intensity by the strength of incoming signals through the shaded area at the receiver, providing a second shaded area of like density, directing a light beam of 10 intensity equal to the normal light intensity on the first shaded area through said second area, comparing the light intensity passing through the second shaded area with that through the first shaded area, and controlling the sensitiveness of a receiving apparatus in accordance with differences in 15 the amount of light passed through each of said areas.

9. The method of controlling the sensitiveness of radio facsimile receiving systems 20 which includes, controlling a light source by received signal pulses, directing the light produced through a shaded area of predetermined density, periodically illuminating 25 a light source of intensity corresponding to normal intensity of said first light source, directing the light beams issuing through said second light source through a shaded area of like density to said first shaded area, 30 comparing the amount of light passed through each of said shaded areas from both of said sources, and controlling the sensitiveness of the receiving system in accordance with variations in the intensities of 35 the said lights passed through each of said areas.

10. In a picture receiving system, a light source, an amplifier, means associated with 40 said amplifier for illuminating said light source and producing an intensity of illumination therein proportional to the strength of incoming signals, means for periodically illuminating a source of constant light intensity, means for comparing the relative 45 intensities of each of said light sources, and means governed by the variations in light intensity of said first source of said constant source for applying a compensating bias potential upon said amplifier, whereby the 50 strength of the received signals is controlled in proportion to the conditions of reception at any given instant.

11. In a picture receiving system, a light source, an amplifier, means associated with 55 said amplifier for illuminating said light source and producing an intensity of illumination therefrom proportional to the strength of received signals, means for periodically illuminating a source of constant light intensity, a bridge balancing means 60 for comparing the relative intensities of illumination from each of said light sources, and means governed by unbalanced conditions in said bridge means produced by the 65 variations in light intensity of said first

source from that of said constant source for applying a compensating biasing potential upon said amplifier, whereby the strength of the received signals is controlled in proportion to the strength of reception at any 70 given instant.

12. In a system for receiving pictures and the like, a receiving and amplifying means for receiving signals from a distant point, a light source, means associated with said receiver and amplifier for illuminating said light source and producing light intensities therefrom governed in accordance with the strength of said received signals, a light sensitive surface for producing pictures having 80 their density controlled by the varying intensities of light shining thereon, a shaded area on one edge of said light sensitive surface, means for directing said variable strength light through said shaded area, 85 a photo cell sensitive to the light projected through said shaded area, a source of constant light intensity, a second shaded area of like density to said first shaded area, means for directing the light issuing from 90 said constant source through said second shaded area, a second photo cell, and means for subjecting said photo cell to said light passing through said second shaded area, means for comparing the relative intensities 95 of each of said light sources by the currents produced thereby through said photo cells, and means controlled by variations in current flow through each of said photo cells for applying a variable controlling bias potential to said receiver, whereby said first named source of light intensity is controlled in accordance with the strength of the received signals at any instant.

13. In a signalling apparatus, means for 105 receiving and recording signals as picture messages thereof, means for determining the average intensity of signal reception at predetermined time intervals, means for comparing the intensity of reception at said chosen time intervals with a predetermined optimum intensity of reception, and means 110 responsive to variations of said received intensities from said optimum intensity for varying the sensitivity of the said receiving 115 means to receive signals.

14. In a signalling system for receiving facsimile messages, means for translating said received signals into light intensities of values proportional to the average intensity of reception at predetermined time intervals, means for comparing the light intensities produced with a constant predetermined normal light intensity value, and means responsive to differences in said light 120 intensity values for controlling the sensitivity of the receiving means.

15. In a signalling system for receiving picture messages, means for producing light 125 at predetermined time intervals of an in-

tensity proportional to the intensity of the received signals, means for comparing the intensity of the light produced with a constant predetermined normal light intensity 5 value, and means responsive to differences in said light intensity values for varying the bias on the receiving means in accordance with the intensity of signal reception at said predetermined time intervals.

10 16. An apparatus for eliminating intensity fluctuations in radio reception systems comprising means for receiving signals, means for amplifying said received signals, means for converting said amplified signal energy 15 into proportionate light intensities for recording purposes, and means for controlling the amplification of said signals over predetermined periods of time in accordance with the intensity of reception during a relatively small portion of said predetermined 20 time period.

17. An apparatus for eliminating intensity fluctuations in receiving systems comprising means for receiving signals, means for recording messages in accordance with said received signals, and means for automatically controlling the sensitivity of said signal recording means in accordance with the strength of signals received during predetermined periods of time separating successive recording actions.

18. An apparatus for eliminating intensity fluctuations in radio reception systems comprising means for receiving signals, means 25 for converting received signals into light impulses of intensities proportionate to the received signals, and means for periodically controlling the received signal energy in accordance with the intensity thereof as 30 received over time periods substantially less than the time period for which the control is to be effective.
